Henry D. VanderCook

Inventor

UNITED STATES PATENT OFFICE.

HENRY D. VANDERCOOK, OF MARSHALL, MICHIGAN.

CLAPBOARDING-GAGE.

Specification of Letters Patent No. 29,206, dated July 17, 1860.

To all whom it may concern:

Be it known that I, HENRY D. VANDERCOOK, of the city of Marshall, in the county of Calhoun and State of Michigan, have 5 invented a new and useful Tool for the Use of Carpenters, which I denominate an "Adjustable Clamping Gage;" and I do hereby declare that the following is a full, true, and exact description of its construction and 10 mode of operation, reference being had to the annexed drawings, making a part of this specification, in which—

Figure 1 is, a perspective view, and Fig. 2 is a vertical section.

15 Similar letters are used to indicate corresponding parts, in both figures.

This tool is intended to facilitate the fitting and attaching of "clapboards" to buildings, and the better to enable others 20 skilled in this particular branch, to construct and use the same, I will now proceed to describe it.

This tool consists of only two principal parts, connected by a thumbscrew and 25 washer. One of these parts, which I designate the clamping stock, is exhibited at A. It is a blade of steel of sufficient thickness and width to confer all the requisite strength, and yet allow of a proper degree of elasticity. The upper end b, is slightly chamfered 30 and the edges rounded off, and the lower half is bent outwardly as seen in Fig. 1, and is provided at the lower end with a handle H which is firmly riveted or otherwise se- 35 cured to it. A steel spur c is securely inserted in the attached end of the handle H and projects outwardly beyond the stock, for the purpose of "dogging" it to the clap- board.

40 D is a metal stud, of a suitable form and length, which is rigidly fastened to the middle of the clamping stock, for the purpose of forming a gage stop, and also to receive the adjustable gage stem G which is at- 45 tached to it at a proper distance apart, by a thumbscrew E, and interposing washer.

The gage stem G, is a thin blade of steel 50 like A but somewhat longer, and with a slot s, like the blade of an ordinary "bevel," for adjusting it by means of the thumbscrew (which passes through the slot) to any re- 55 quired height. The upper part of G is bent at right angles so as to form an offset which I term the "guard," as seen at e, for receiv- ing and holding the piece of clapboard, to be fitted and nailed to the building.

In Fig. 2, F represents a broken section of studding, to which the clapboards I, I are nailed, and J exhibits a piece of clapboard (broken off) in the guard e, ready to be 60 fitted in place.

The outer line of the "corner board" and "face casings" of the building, is indicated by the dotted line x.

The common mode of fitting clapboards, 65 or "siding" to buildings, is to mark with compassed on the fastened "course," the width to weather and then drive in tack nails to hold up the next course while being fitted and nailed. This practice, besides being 70 laborious and consuming much time, is really detrimental to the building; for owing to the intervening space between the board and framing where these guide nails are driven, they are almost sure to splinter the wood, 75 and leave bad jagged holes, when they are withdrawn.

By the use of my clamping gages, the use of tack nails is entirely dispensed with, and the clapboards are fitted and nailed on to a 80 building with great facility, accuracy and despatch, in the following manner.

Two courses of clapboards having been attached to a building in the ordinary way, I adjust two of these gages, by means of 85 the thumbscrew, so that the distance from the stud D to the shoulder of the guard e, shall be the proper distance to weather; then, by one or more fingers inserted through the ring of the handle H, I push the blade of the 90 clamping stock A between the two nailed courses until the stud D strikes against the lower edge of the upper clapboard, when I "dog" it to the lower clapboard by a slight tap on the handle, which drives the short 95 spur C into the wood. In order to effect this the lower end of the gage stem must be sprung outwardly so that when it is dogged fast, it will assume the form as in- 100 dicated in Fig. 2, and as the handle passes freely through the slot, there is no strain on the gage stem, or any danger of displacing it, by pulling on, or tapping the handle of the clamping stock A. The other gage hav- 105 ing been adjusted in a similar manner, I take the length of clapboard to be fitted and insert it between the guards so that it rests on the shoulders, when the spring of the blade holds it firm against, the casing. It is then scribed, withdrawn, cut off to the 110 scribe marks and replaced between the "guards," when it is nailed fast. The two

gages are now drawn out from between the clapboards by the handles and inserted in the same manner just described, between the new courses, ready to receive the next length, 5 and so on until the building is completely inclosed.

What I claim as my invention, and desire to secure by Letters Patent, is—

The mode of holding clapboards, in true 10 parallel lines, to a building while they are

being scribed, fitted and nailed; by means of the clamping stock A and attachments, in combination with the adjustable gage stem G, constructed and used substantially in the manner, as herein described and set forth. 15

HENRY D. VANDERCOOK.
